[57] **CLAIM**

The ornamental design for a support bracket for a cage mounted poultry watering device or similar article, substantially as shown and described.

DESCRIPTION

FIG. 1 is a prospective view taken from the bottom, front, and left side of a support bracket for a cage mounted poultry watering unit or similar article showing my new design;

FIG. 2 is a left side elevational view thereof;

FIG. 3 is right side elevational view thereof;

FIG. 4 is bottom plan view thereof;

FIG. 5 is a top plan view thereof;

FIG. 6 is front elevational view thereof;

FIG. 7 is a rear elevational view thereof; and

FIG. 8 is another perspective view taken from the bottom, front and left side thereof, the fragmentary broken line representation of a wire cage and a watering unit are for purposes of illustration only.
